UNITED STATES PATENT OFFICE.

ALBERT O. TOWNS, OF HUDSON, NEW HAMPSHIRE, AND FRANK W. LYNDE, OF MELROSE, MASSACHUSETTS, ASSIGNORS, BY MESNE ASSIGNMENTS, TO W. PIERREPONT WHITE, HUGH WHITE, AND CLARENCE B. CROUSE, OF UTICA, NEW YORK.

MACHINE FOR SEWING ON BUTTONS.

SPECIFICATION forming part of Letters Patent No. 643,614, dated February 13, 1900.
Application filed November 6, 1895. Serial No. 568,152. (No model.)

To all whom it may concern:

Be it known that we, ALBERT O. TOWNS, residing at Hudson, in the county of Hillsborough and State of New Hampshire, and FRANK W. LYNDE, residing at Melrose, in the county of Middlesex and State of Massachusetts, citizens of the United States, have invented a new and useful Improvement in Machines for Sewing on Buttons, of which the following is a full, clear, and exact description, reference being had to the accompanying drawings, forming a part of this specification, in explaining its nature.

The invention relates to a machine for sewing on buttons having the features herein-after described.

In the drawings, Figure 1 is a view, partly in side elevation and partly in section, of a machine containing the features of our invention. Fig. 2 is a view in plan with the parts above the bed-plate removed. Fig. 3 is a view of the bar F and its connections. Fig. 4 is a similar view of the bar H. Fig. 5 is a view of the button. Fig. 6 is a view of the button-holder D, showing its connection with the presser-foot. Fig. 7 is a cross-section on the dotted line 7-7 of Fig. 2. Fig. 8 is a view of the end of the bar H. Figs. 9, 10, 11, 12, and 13 are views showing different ways of arranging the thread in sewing buttons.

Our invention is represented as applied to the machine known as the "Standard" sewing-machine. It has a head A and a horn or cylinder B similar to those of the said Standard machine, the horn or cylinder, however, being widened near the point of its attachment to the bed B' to provide room for a portion of the operating mechanism hereinafter described. The mechanism for performing the stitch, including the needle, take-up, shuttle, and shuttle-operating devices, are like those of the said Standard machine. The fabric to which the button is secured is supported by a feed-plate C which is provided with lateral and forward-and-backward movements in relation to the stitching mechanism, as hereinafter specified, and the buttons are held to the material during the operation of

sewing them thereto by a holder D, having a circular or other hole or a recess or notch through which the needle plies and adapted to have a vertical movement toward and from the plate C, and to hold the button upon the fabric during the sewing operation by being placed upon it and the fabric and being held thereto. The said button-holding plate D is also provided with lateral and forward-and-backward movements in unison with the cloth-plate C and while held down upon it. The mechanism for providing the feed-plate and the button-holder with these movements comprises a cam-disk E, having in its under side the cam-groove e and in its upper side the cam-groove e'. This cam-disk is in the inner end of the horn or cylinder, and it is for the purpose of affording room for it that this section of the cylinder has been enlarged. The cam is mounted upon the stud e², which is supported by the boss e³ upon the inside of the cylinder B, and it is revolved by means of the bevel-pinion e⁴ on the shaft e⁵, the teeth of which mesh with the bevel-teeth e⁶ of the cam-disk. The lower cam-groove operates the mechanism which determines the forward-and-back movement of the work-holder and button-holder, and the cam-groove e' provides the said holders with lateral movement. The said last-named cam-groove is connected with the work-holding plate C by means of a lever f, (see Fig. 2,) pivoted at f' and engaging by the adjustable pin f² a slide-bar f³, the slide-bar having a straight movement back and forth lengthwise the horn. The extent of this movement is varied by forming in its rear end a slot f⁴ and by forming in its operating-lever f a corresponding slot f⁵ and by making the pin f², connecting these parts, adjustable lengthwise the slots. The greatest throw of course will be provided the slide-bar when the pin is farthest removed from the pivot-point of the lever f, and from that point the throw will be decreased according as the pin is moved toward said pivot. To the forward end of the slide-bar there is pivoted at f⁶ a bar F, which carries at its end the work-sup-

port C. It will be understood, of course, that the work-support has in it a hole c of a size to include the holes of the button. It will be seen that the cam e' and the connecting devices described provide the work-support with lateral movements or movements cross-wise the usual line of feed and that there is also provided means by which movements in the direction of the usual line of feed and at right angles to the length of the bar or horn may be provided the work-support. The devices for providing the work-support with this movement are shown in detail in Figs. 3 and 4, and they consist of a disk or short shaft G, mounted in the cross-bar g of the horn, having extended across its upper face a guideway g' , in which is a sliding block g^2 , attached to the under surface of the work-holder bar F. This disk or shaft is adapted to be turned to cause this guideway to occupy any desired position—that is, it may be in line with the center of the said bar F, when it will serve to steady the movements of said bar; but it will impart to the said bar no side movement, the bar then moving longitudinally only, or it may be moved to an angle from this mean line to one side or the other of it, and this position of the guideway will cause an oblique movement to be given to the bar F when said bar is moved longitudinally, and consequently a lateral movement or a movement transverse to the usual direction of the feed will be imparted to the work-holder C, and the extent of this lateral movement of the said work-holder will vary according to the length of the longitudinal movement of the said bar. It will be understood that these movements are imparted to the bar F because as the said bar is moved longitudinally, being pivoted at its inner end, the guideway will cause its outer end to be moved in one direction or the other, according as the guideway is turned. The position of the guideway is governed by the cam e , with which it is connected by the slide-bar H, the said bar having the cam-pin h , which enters the cam-groove e , and a forked end h' , which straddles the stud e^2 , which thus acts to hold that end of the bar. The outer end of the bar is connected with the shaft or disk G by the pin h^2 , which is at a right angle to the guideway formed therein and which has a block h^3 , which is received by the recess or pocket h^4 in the bar H, the forward end of the slide-bar H sliding in the slideway h^5 in the cross-bar g and beneath the swiveling disk or shaft. The extent of movement of the slide-bar H governs the angle of the guideway g and may be varied to any extent by varying the cam-groove e , and the cam-groove of course fixes the time of the change in the angle of the guideway. It will be understood, of course, that it is movable so as to throw the work-holding plate either to one side or the other side of the central line of the horn and at any desired time in respect to the time of the lateral movement. The button-holder D is given

the movements of the work-holder by being attached to the arm D' at d , the arm preferably curving upwardly and extending backwardly and downwardly to the point f' , where it is attached to the bar F. The button-holder is attached to the arm D' in a manner to permit it to be moved vertically in relation to its end by means of the long pin d^2 , which extends from the block d^3 through a hole in said end d . This block carries the button-holder D, which is in the form of a plate having an extension entering a recess or groove in said block and secured therein by a screw or any other desired way so as to be movable and removable. This block d^3 is connected with a bracket d^4 , rigidly secured to the usual presser-bar. This bracket is connected with the block d^3 by the connection d^5 in a manner to impart the downward movement of the presser-bar to the button-holding plate D and yet permit of the universal horizontal movement of the button-holder plate in relation to the presser-bar. The tension or pressure on the button and fabric is controlled by the usual spring and nut of the Standard presser-bar, and the bar may be operated by the usual lift.

In use the button and the fabric upon which it is to be sewed are both clamped between the cloth-plate C and the button-holder plate D, and upon the starting of the machine a zigzag or hour-glass stitch, like that shown in Fig. 13, will be sewed through the holes of the buttons, according as the work-plate and button-holder are moved by their operating-cams and controlling devices. If the swiveling disk is made inoperative by changing the location of the block h^3 from the short recess or pocket h^4 to the long recess or pocket h^6 of the bar H, a stitch known as the "single-bar" stitch will be sewed. By the use of a pair of needles mounted upon the needle-bar so that a straight line passing through both their centers would be at right angles to the line of the shaft and giving the holder-plate and button-plate the lateral movement only last described a double-bar stitch would be sewed through the button in half the time usually required for making this stitch.

Any suitable starting and stopping device for permitting a predetermined number of stitches may be used upon the machine.

It will be understood that the machine employs two threads, and that in the making of the "hour-glass" stitch, so-called, the transfer of the button is such and the interlocking of the threads that a knot is formed at the end of each full stitch. In other words, the threads fastening the buttons to the material are knotted as many times as they repeat the full stitch. It will be seen that the hour-glass stitch is made up of the bars which are at a right angle to the wale of the garment and two intersecting or crossing bars. This forms a stitch made by two threads and very securely fastens the button to the fabric.

It will be seen that if the lateral movement takes place while the disk G is at rest an

oblique stitch is laid; but if the disk G oscillates while the bar F is at rest a straight forward stitch will be laid, and if the disk G oscillates at and in the same time of the movement of the bar F a straight lateral stitch will be laid. The operative cams can be timed to do this.

By combining an automatic button-shifting mechanism with a sewing-machine work-support made in the form of a horn or cylinder B, within which is contained the shuttle or equivalent loop-taking device which operates with the needle in the formation of the stitches, we have adapted a button-sewing machine for attaching flat buttons to hollow or tubular articles by stitches passing alternately through different holes of such buttons, as will be readily understood by those skilled in the art to which our invention relates. Also by connecting the movable button-holder D to the forward end of the arm D', which from its point of connection with its operating-slide f⁶ extends upward and then forward and then downward to its point of connection with the said button-holder, so as to form a loop of considerable size, it will be apparent that proper space is afforded within said loop for a considerable amount of work or material when the same is being shifted transversely of the horn or work-supporting cylinder, thus adding to the convenience in the use of our improved machine in attaching buttons to garments where it is desired to have proper space for a considerable portion of the material beneath the arm A of the machine and to the right of the needle.

Having thus fully described our invention, we claim and desire to secure by Letters Patent of the United States—

1. In a machine for sewing on buttons, the combination with a stitch-forming mechanism, a movable work-support and a movable button-holder connected with said support and between which work-support and button-holder the work to which the buttons are to be attached is to be held, of a normally-stationary, pivoted or swiveling device or disk, as G, provided with a guideway, a pin or slide working in and longitudinally of said guideway at each reciprocation of the needle and connected with said work-support and button-holder to impart horizontal movements to the latter in one direction, mechanism for reciprocating said button-holder in a plane transverse to that induced by said guideway, and automatic mechanism for periodically turning said pivoted device or disk to cause the direction of movement of said work-support and button-holder to be changed.
2. In a machine for sewing on buttons, the combination with a stitch-forming mechanism, a movable work-support and a movable button-holder connected with said support and between which work-support and button-holder the work to which the buttons are to be attached is to be held, of a normally-sta-

tionary, pivoted or swiveling device or disk, as G, provided with a guideway, a pin or slide working in and longitudinally of said guideway at each reciprocation of the needle and connected with said work-support and button-holder, and two cams, one of which is connected with said work-support and button-holder to reciprocate the same, and the other of which is connected with said swiveling device or disk and which acts to automatically turn the latter to cause the direction of movement of the said work-support and button-holder, induced by said guideway, to be changed.

3. In a button-sewing machine, the combination with a stitch-forming mechanism, a work-plate and a button-holder, of a presser-bar connected to said button-holder by a device which serves to communicate the pressure of said presser-bar to said button-holder, said connecting device having a positive and universal-joint connection with said presser-bar so that said button-holder may be moved vertically thereby, or in any desired horizontal direction independently thereof, and automatic mechanism for shifting said button-holder beneath the needle for the purpose of forming stitches in the different holes of a button to be stitched to a garment.

4. In a machine for sewing on buttons, the combination with a stitch-forming mechanism, of a button-holder, as D, a normally-stationary, swiveling device or disk, as G, provided with a guideway and with which guideway said button-holder is connected, a rotating cam, as e, a sliding bar H connecting said cam with said swiveling device or disk and thereby serving to automatically shift the position thereof after a predetermined number of stitches have been made, and a cam, as e', also connected with said button-holder and serving to reciprocate the latter beneath the needle at each stitch and in a plane different from the plane of the movements induced by said guideway.

5. In a button-sewing machine, the combination with a button-holder, as D, of a swiveling device or disk, as G, provided with a guideway and with which guideway said button-holder is connected, a cam, as e, a slide-bar, as H, connecting said cam with said swiveling device or disk, said slide-bar being provided with a short recess or pocket h⁴ and the long recess or pocket h⁶, and the said swiveling device or disk being provided with a block h⁸, which may be placed in either of said recesses or pockets according as it may be decided to oscillate said swiveling device or disk, or to permit the latter to remain stationary, and a cam, as e', connected with said button-holder for imparting reciprocating movements thereto.

6. In a button-sewing machine, the combination with a stitch-forming mechanism, of the work-support C, the button-holder D arranged above but connected with said work-support, the normally-stationary, swiveling

device or disk G provided with the guideway g', the bar F having a pin or slide working in said guideway, the arm D' connecting said button-holder with said arm F, a rotating cam, as e', connected with said bar and operating to reciprocate the latter and the work-support and button-holder in one plane, at each stitch, and a cam, as e, connected with said swiveling device or disk and serving to automatically shift the latter, after a predetermined number of stitches have been made, to change the direction of movement induced by said guideway.

7. In a button-sewing machine, the combination with a stitch-forming mechanism, of the work-support C, the button-holder D connected with said work-support, a presser-bar, a rigid rod or bar, as d⁵, having a positive, universal-joint connection with said presser-bar and button-holder so that the latter may be lifted by the former or may be moved horizontally in any direction independent thereof, and so that the pressure of said bar may be communicated to said button-holder through said rigid rod or bar, and automatic mechanism for shifting said work-support and button-holder in any desired direction to cause the needle to penetrate the different holes of a button held by said button-holder.

8. In a button-sewing machine, the combination with the stitch-forming mechanism, of the work-support C, a button-holder D, a presser-bar provided with a bracket d⁴, the connecting rod or bar d⁵ having a universal-joint connection with said bracket and said button-holder, mechanism for automatically shifting said button-holder beneath the needle, said universal-joint connection permitting of free movement of the latter relative to the presser-bar when moved by said automatic mechanism and said connecting rod or bar d⁵ connecting said button-holder and bracket so that said button-holder will be lifted from the work when said presser-bar is raised, and said rod or bar also affording

means whereby the pressure of said presser-bar will be communicated to said button-holder when the latter rests upon the work, to hold a button in sewing position.

9. In a button-sewing machine, the combination with the stitch-forming mechanism, of the work-support C, the button-holder D connected therewith, the normally-stationary, swiveling device or disk G provided with a guideway operatively connected with said work-support and button-holder, a cam e connected with said swiveling device to automatically shift the same periodically or when a predetermined number of stitches have been made, the cam e', the slide-bar f³ connected with said work-support and button-holder, and the lever f provided with a cam-pin or roller-stud engaged by said cam e', said lever being operatively connected with said slide-bar, and said cam being constructed and rotated to reciprocate said work-support and button-holder once at each two reciprocations of the needle.

10. In a button-sewing machine, the combination with the stitch-forming mechanism, of the work-support C, the button-holder D connected therewith, the normally-stationary swiveling device or disk G provided with a guideway operatively connected with said work-support and button-holder, a cam e connected with said swiveling device to automatically shift the same when a predetermined number of stitches have been made, the cam e', the slide-bar f³ connected with said work-support and button-holder and provided with the slot f⁴, the lever f provided with a cam-pin or roller-stud engaged by said cam e' and having the slot f⁵, and the pin f² forming an adjustable connection between the slotted portion of said slide-bar f³ and said lever f.
